EXPANSION RAIL JOINT

Hans Otto Hoffmann, Lausanne, Switzerland

Application October 27, 1943, Serial No. 507,813
In Switzerland June 28, 1943

3 Claims. (CL. 238—219)

1

It is known that a railway wheel rolling over the gaps at joint between the ends of rails causes concussions, whereby the permanent way, and also the rolling material are subjected to strong wear. Due to the fact that, lately, the speed of trains has been considerably increased, also the weight of the rolling material, including the net load, these inconveniences have attained a degree of unbearableness and, therefore, effective remedial measures are urgently required. Efforts have been made to counteract drawbacks of this nature by increasing the rolling length of the rails, and by welding the rails to form so-called long rails, whereby the number of gaps at joint is considerably reduced. For various reasons, the length of such long rails is, however, limited. Long rails can only accomplish their true object, if means can be found to connect them by a rail joint, which does not cause any concussions, and permits expansion of the rails. This task is accomplished by the present invention.

The present invention refers to an expansion rail joint, whereby the ends of the rails to be connected, which are attached, at a certain distance from each other, to rail chairs, have full profiles, i. e. the rail-head is not undercut, and are provided with a groove each, in the centre, in the longitudinal direction of the rails, an interchangeable connecting-web being positioned on shoulders formed by the grooves in the ends of the rails, its length being dimensioned in such a manner that, on both sides of its ends, in the grooves positioned in the rail-ends, expansion gaps are provided, this connecting web being immovably held fast, independently of the rails, by a spur provided on its lower side and reaching down, at least, to a position between the bearing-plates of the rail chairs.

The enclosed sketch shows two embodiments of the object of the present invention, by way of example. The sketch shows:

Fig. 1 a side-view of a first form of embodiment of an expansion rail joint, partly in section;

Fig. 2 a top-view thereof;

Fig. 3 a section on the line I—I in Fig. 2;

Fig. 4 is a side-view of a second form of embodiment of an expansion rail joint, partly in section;

Fig. 5 is a top-view thereof;

Fig. 6 a section on the line II—II in Fig. 5.

On the tie 1 of double width, according to the first example, the ends of the rails 3 and 3' respectively are wedged in such a manner in two rail chairs 2 and 2' respectively that there is a space D between the front surfaces of the rails

3 and 3'. Toward their ends the profiles of the rails 3 and 3' are altered from the standard profile of a flat base or foot and a bulging head, with an intermediate, comparatively thin, supporting web, to a profile in which the portion between the base and the head is as thick as the head and may become thicker downwardly so as to meet the base near the outer edges thereof. This altered profile is hereinafter referred to by the term "full-profile." Such a development of the ends of the rails 3 and 3' can be effected by welding full-profiled end-pieces to the ends of rails of standard profile. These end-pieces of the rails 3 and 3' can, however, also be manufactured of cast steel in one piece. In the rail chairs 2 and 2' respectively, the rails 3 and 3' respectively are held on the exterior part by means of a steel key 4, provided with a spur 5, which is guided between the rail chairs 2 and 2' in such a manner that it can move in a vertical, but not in a horizontal direction. A head 6 at the upper ends of the rail chairs 2 and 2' prevents the steel key 4 from getting out of the upper part of the space between the rails 3 and 3', and the rail chairs 2 and 2' by means of wooden fox wedges, the inner part 7 of these wedges being secured against dislocation in the longitudinal direction by a channel 8 screwed on to them, reaching down between the bearing-plates of both rail chairs 2 and 2' and, thereby acting as an anchor. The exterior part of the wooden fox wedges, however, can be moved in order to tighten up the wedge in a longitudinal direction. The inner part 7 is narrower at its upper than at its lower part, whereas the outer part 9, inversely, is wider at its upper than at its lower part, in such a manner that the inner part 7 is held by the outer part 9, which also is secured by means of a head at the upper part of the rail chairs 2 and 2'. In case of loosening of the wooden fox wedges 7, 9, the steel key 4 drops down, under the effect of its weight and, thereby, secures the keying, sliding down the slightly inclined side surface of the ends of the full-profiled rails 3 and 3' and, for this reason, any dangerous loosening cannot take place. The arrangement of the steel key 4, which strictly takes up the forces produced, on the outer part of the rails 3 and 3', provides for the fact that the rails are always under strain from the inner to the outer part, due to the lateral components of the forces produced by the rolling material.

The full-profiled ends of the rails 3 and 3' are provided, in the centre, with grooves 10 and 10' respectively in the longitudinal direction of the

rails. These grooves 10 and 10' do not extend from top to bottom of their entire length in one piece, but form shoulders 11 and 11' respectively. A connecting-web 12 is inserted into the grooves 10 and 10', and this web lies on the shoulders 11 and 11'. On its lower part, this connecting-web is provided with a spur 13, which reaches down to below the base of the rail, at least to the upper edge of the tie, its end being fitted into the bearing-plates of both rail chairs 2 and 2', in such a manner that the connecting-web 12 cannot be dislocated. The length of the grooves 10 and 10', on the one hand, and of the connecting-web 12, on the other hand, is dimensioned in such a way that there is an expansion gap d and d' respectively on each side of the connecting-web 12, whereby the sum of the lengths of these expansion gaps $d+d'$, is always equal to the distance D , in which the front surfaces of the rails 3 and 3' lie apart from each other. The convexity of the heads of the rails 3 and 3' is gently chamfered up to the plane of the upper edges of the grooves 10 and 10' respectively, with which the surface of contact of the connecting-web 12 lies flush. On a length exceeding the maximum width of the expansion gaps d and d' respectively, the upper edges of the grooves 10 and 10' lie in the plane of the surface of contact of the connecting-web 12, and from there the side-walls of the ends of the rails 3 and 3' are chamfered and rounded off towards the ends of the rails. The purpose of this arrangement is to gradually force even a wheel not rolling normally on the entire width of the rail-head to roll off on the connecting-web 12, thereby avoiding concussions, under all circumstances, when running over rail joints.

In the case of the expansion rail joint described above, both rails 3 and 3' can expand independently from each other. In Fig. 1, whereby an illustration of this relation is furnished, the rail 3 is shown with maximum expansion, whereas the rail 3' does not expand at all. A particular advantage is offered by the symmetric formation of the ends of the rails and of the connecting-web 12, both as regards the longitudinal and the transverse axis, whereby the laying of the lines is considerably simplified. The expansion rail joint described works in such a manner that the formation of cracks and steps at the ends of the rails is avoided. If one of the rail-ends sinks under the wheel-load, the connecting-web 12 also sinks, and as soon as it is affected by the load, it acts on the rail-end lying opposite, by loading it. The expansion joint, therefore, works in an elastic manner, thus ensuring the running-through of rolling loads, without causing concussions. The depression of the rails under the load, and also the previous lifting off of the rails are effected in a supple manner.

The development of the expansion rail joint, according to the present invention, permits the use of any length of expansion gaps. By keying, or otherwise anchoring the rails on ties, the normally unimpeded expansion of rails can, under certain circumstances, be checked to a very considerable extent, according to requirements, by basing on modern knowledge of long-rail track laying. Inasmuch as the connecting-web 12 is arranged to be immovable, independently of the rails 3 and 3', it can be ascertained at any time by comparing the expansion gaps d and d' at both ends of the connecting-web 12, whether the checking of the expansion is being observed, and a control regarding the attitude of the rails in other respects is rendered possible. This is par-

ticularly important, because it is known that rails have the tendency to creep and to push together to groups, and this should always be avoided in the case of long-rail lines. According to the present invention, it can be ascertained in an indisputable manner, and at an opportune moment, which of two or several rails starts creeping, and whether the checking of expansion to be provided is adhered to, whereby it is possible to meet any inconvenience arising in due time. The checking of the expansion is effected by means of the resistance of ballast, and possibly also by additional arrangements at the joint itself, whereby ribbed iron wedges are advantageously employed, instead of wooden wedges.

Connecting-webs, which are worn out, can easily be replaced and freshened up. All wedges are rounded off and, thereby the wear and tear is negligible. Worn out pieces of rail-ends can be repaired again by a welding operation.

In the example of an expansion rail joint shown in Figs. 4-6, 14 represents the tie of double width, 15 and 15' the rail chairs, and 16 and 16' the rails. Also these rails 16 and 16' are provided with full profiles at their ends. On the outer part, the rails 16 and 16' are held in the rail chairs 15 and 15' by means of a steel-key 17, which is immovably held by a projecting part 18, co-operating between the rail chairs 15 and 15', in the longitudinal direction of the rails. On the inner part of the rails 16 and 16', wooden fox-wedges are arranged, their under part 19 being secured against dislocation in a longitudinal direction by means of an anchor 20 reaching into the bearing-plates of the rail chairs 15 and 15'. The outer part 21 of the wooden fox wedges is, however, movable in a longitudinal direction, in order to tighten up the wedges. So far, the formation is exactly the same, as in the example described above. The full-profiled ends of the rails 16 and 16' are provided, in the centre, with grooves 22 and 22' respectively running in a longitudinal direction, which also do not extend from top to bottom of their entire length in one piece, but form shoulders 23 and 23' respectively. A connecting-web 24 is inserted into the grooves 22 and 22', this web being positioned on the shoulders 23 and 23' and provided, on its lower part, with a spur 25, which reaches down, at least, to the upper edge of the tie, and is held between the bearing-plates of the rail chairs 15 and 15'. The length of the grooves 22 and 22', on the one hand, and of the connecting-web 24, on the other hand, is dimensioned in such a manner that, on each side of the connecting web an expansion gap d_1 and d'_1 remains open. The middle part 26 of the connecting web 24 has a rail-head profile with chamfered and rounded off edges on both sides. In order to take up this rail-head profiled middle part 26 of the connecting-web 24, the lateral expansion gaps between the ends of the rails 16 and 16' which, in the example previously described, are equal to the sum of the expansion gaps d and d' , are subdivided into two expansion gaps, their length corresponding to that of the expansion gaps d_1 and d'_1 . The sum of the length of d_1 and d'_1 corresponds to the distance D_1' , in which the front surfaces of the rail-ends 16 and 16' lie apart from each other. This formation of the expansion rail joint may generally be considered as satisfactory, in order to reduce the length of the expansion gaps on the side surface of the rail to the length of the expansion gaps d_1 and d'_1 ; it is, however, of particular advantage, provided

an expansion rail joint should exceptionally lie in a rail-curve, in order to safely avoid climbing of the wheel flanges, even in the case of strongest contraction of rails, i. e. maximum opening of the expansion gaps.

I claim:

1. A rail joint especially intended for joining ends of rails of great lengths spaced apart at their ends by substantial gaps so as to provide for expansion thereof without application of stress in the rails which rails throughout the part of their lengths remote from their ends are comprised by rail base flanges, wheel supporting heads and webs of less width than the heads supporting said heads, the webs of said rails in the vicinity of the adjacent ends being thickened laterally so as to be thicker than the webs remote from the end portions and of substantially the same thickness as the width of the rail heads, the upper portions of said rail ends each being provided with longitudinally extending central grooves, said grooves extending in depth less than the entire depth of the rails, thus providing shoulders at their bottoms, and a replaceable tread-bridge rail-top insert accommodated in the said grooves resting on the bottom shoulders of said grooves and bridging the gap between the rail ends with the upper edge of the insert flush with rail heads, said insert being of a length shorter than the combined length of said grooves and the gap between the rail ends to provide gaps between the ends of said insert and the opposite end faces of the said grooves, a pair of bed plates extending laterally of said rails and spaced apart, longitudinally of said rails, a pair of bilateral chairs resting on said bed plates having wedge means for laterally bracing the said rail ends and for aligning the rails and the central grooves in the end portions of the rails, said insert having a downwardly projecting bottom lug adapted to be engaged in the space between the bed plates of the said chairs for the purpose of immovably

anchoring the said insert irrespective of longitudinal movements of said rails.

2. A rail joint as defined in claim 1, and in which all of the upper edges of the rails where the grooves are formed and the upper edges of the insert are rounded off.

3. In a rail joint as defined in claim 1, and in which the upper parts of the recesses in the rails adjacent their ends are of the full width of the rail heads, the tread bridge insert having a central upper part of equal width to the rail head, said central part being disposed in the parts of the recesses of full rail head width, the parts of the recesses and the part of the insert which are of the full rail head width being symmetrical to the gap between the rails, and the part of the insert of full rail head width being of such length as to provide gaps between the ends thereof and the end faces of the parts of the recesses of full rail head width, the sum of widths of the latter gaps being equal to that of the gaps between the ends of said insert and the end faces of said recesses and also equal to the width of the gap between the rail ends.
